LIPSTICK HOLDER

Anthony G. Rosa, Lyndhurst, N. J.

Application April 6, 1944, Serial No. 529,706

3 Claims. (Cl. 206—56)

This invention relates to new and useful improvements in lipstick holders, and it has for its purpose to provide a device, whereby a lipstick may be securely screened, and, when the use of the same is desired, may automatically be made to adequately serve, by having said lipstick give off a sufficient, finely squeezed, creamy amount from the top of the latter, by shaving said top of the lipstick through a special construction of the upper portion of the holder of the lipstick, as will be hereinafter fully described.

The construction of my device is further to the effect that when said lipstick is not in use, a lid may be closed upon the latter, and thereby automatically discontinue the urgency, due to a spring arrangement, of the lipstick to move upward to a serving position, which urgency is again obtained automatically upon opening the lid of the holder of the lipstick previously to bringing the latter into use.

With the above and other objects in view, this invention consists of the novel features of construction, combination and arrangement of parts, hereinafter fully described, claimed and illustrated in the accompanying drawing, forming part of this application, and in which similar characters of reference indicate corresponding parts in all views, and in which:

Figure 1 is a vertical transverse sectional view of my device, having a lipstick arranged therein. Figure 2 is a top plan view of the lipstick holder.

Figure 3 is a view similar to Figure 2, and showing a modification in construction of the top portion of said lipstick holder; while

Figure 4 is also a transverse section of a lipstick holder, showing the means for arresting the upward motion of the lipstick proper, in operation, and showing a detachable cover.

Referring more particularly to the drawing, the numeral 10 indicates a lipstick of the more conventional kind; said lipstick is inserted in a holder 11 through the open bottom of the latter and is held in place by a member, or carriage, 12 adapted to slide within said holder. A cap member 13 is detachably mounted upon the lower part of the holder 11 and may be secured to the latter in any suitable manner, for instance by snap-fasteners. Inside said cap member 13 is arranged a spring 14, which acts upon the bottom 22 of the carriage 12 and through the latter urges the lipstick 10 steadily upward within the holder 11 into serviceable position.

The holder 11 has an angular, or round, roof-shaped top, as shown, respectively, at 15 and 16 in the Figures 2 and 3. The said roof is in both cases formed with a plurality of slots, or slits, 17

therein to the effect that due to the pressure of the spring 14, the top 18 of the lipstick proper will, upon coming into contact with said slits, give off a "shave" or creamy "fluffy" mass, excellently adapted for the use by a lady in obtaining the result desired from applying a lipstick.

The lipstick holder is formed with an opening 19 oppositely disposed in each side thereof. A bar, or thin strip, or preferably resilient material, 20 is arranged oppositely upon each side inside the said holder and in alignment with the openings 19; said bars terminate at their upper ends in small projections, or studs, 21 protruding through the openings 19 in the lipstick holder, as may be seen in Figure 1.

When the lipstick is not in use, a closure cap 23 is fastened upon the top of the holder to the effect that said cap will exert an inward pressure upon the projections 21, and thereby, in turn, cause a squeeze of the bars 20 upon the lipstick proper, with the result of arresting the upward movement of the latter, as shown especially in Figure 4, thereby preventing any further automatic discharge of the lipstick material, when not in use.

It is obvious that changes may be made in the form, construction and arrangement of the several parts, as shown, within the scope of the appended claims, without departing from the spirit of the invention, and I do not, therefore, wish to limit myself to the exact construction and arrangement shown and described herein.

What I claim as new, and desire to secure by Letters Patent of the United States, is:

1. In a device of the class described, a cylindrical tube adapted to receive a lipstick therein, said tube having an open bottom, and being formed with slits in its top, a carriage slidable within said tube and supporting the lipstick proper, and a spring actuating said carriage, whereby to urge the lipstick upward, said tube being formed with openings oppositely disposed in the wall thereof, bars oppositely arranged inside said tube and adapted to arrest the upward motion of the lipstick, said bars terminating in studs projecting through said openings, a cap for closing the bottom of the tube, and another cap made to engage the top of the tube and actuate said studs, substantially as and for the purpose set forth.

2. In a device, as claimed in claim 1, and wherein the roof of said tube has an angular shape.

3. In a device, as claimed in claim 1, and wherein the roof of said tube has a round shape.

ANTHONY G. ROSA.
